UNITED STATES PATENT OFFICE

JOHN F. SKIRROW, OF SOUTH ORANGE, NEW JERSEY, ASSIGNOR TO POSTAL TELEGRAPH-CABLE COMPANY, OF NEW YORK, N. Y., A CORPORATION OF NEW YORK

METHOD OF AND APPARATUS FOR COLLECTING TELEGRAPH MESSAGES

Application filed October 2, 1929. Serial No. 396,710.

This invention relates to a method of and apparatus for collecting telegraph messages. All existing methods of filing telegrams with a telegraph company have some disadvantages. If the customer calls for a messenger, time is lost while the messenger is on his way for the message and returning with it to the telegraph office. If the message is telephoned to the telegraph office, it takes the time of the customer or an employee at each end of the line until the message is completed, and there is always a possibility of error in copying the message. If a printing telegraph is used by the sender of a message, there is the expense of maintaining the machine and the salary of an operator to be considered and also danger of errors due to the machine or the operator.

One object of this invention is to overcome these difficulties in so far as large buildings are concerned.

Another object is a rapid and accurate system for forwarding telegrams from a sender to a central office or branch office with a minimum of expense.

Another object is a remotely controlled electrically operating locking mechanism for a mailing chute.

In order to do so, a chute of suitable dimensions is installed in a building extending from the upper part of the building and terminating at an office in the basement which will be in charge of an attendant. This office will be provided with transmitting and receiving pneumatic tubes connecting with a central or branch telegraph office. Openings in the chutes with hinge covers are provided on each floor. The chute lids may be provided with locks, and keys may be furnished to customers, but the preferred method would be to control the locking of the chute lids by an electric circuit from the basement, and in this way there would be no danger of messages being deposited in the tube when the office is closed. Means are provided for operating a signal circuit when any lid is opened in order to notify the attendant that a message has been deposited in the tube and to indicate the particular lid which was opened. When the message reaches the office in the basement the

attendant can operate a signal associated with the particular box opened to assure the customer that the message has been received.

In the drawings comprising but a single sheet of five figures, numbered Fig. 1 to 5 inclusive one embodiment of the invention is illustrated.

Fig. 1 is a detailed view of a section of the building chute.

Fig. 2 is a schematic diagram of one embodiment of the system from subscriber to central office.

Fig. 3 is a schematic circuit diagram of an electrically controlled chute lid locking device.

Fig. 4 is a schematic circuit diagram of the visible signal circuit.

Fig. 5 is a detailed view of the building chute at the basement office together with its associated visible and audible signal circuits.

Like reference characters designate corresponding parts throughout the several figures.

Referring to Figs. 1 and 2 of the drawings, 9 is the telegram chute, 11 is a box arrangement built around an opening in 9. There will be one of these openings on each floor. A cover 10 is hinged at 13, and when opened, permits access to the interior of the chute. A lamp cap 12 is inserted in the side of the box 11. Printed directions for operating the chute, or the address and telephone number of the nearest telegraph office in case the chute is locked, may be indicated on the plate 14.

Referring to Figs. 1, 2 and 4, when a subscriber desires to forward the typewritten message to the basement office the lid 10 on the floor where the subscriber's office is located is opened to deposit the message 57 (Fig. 2). This closes the contacts 20 and 21 completing a circuit from ground at 22 through conductor 36 and coil 37 of annunciator 38 in the basement office to grounded battery 35, operating the annunciator. Coil 39 of annunciator 40 indicates one of a series of additional annunciators associated with various floors in the office building, which may be operated in the same manner. When the deposited message 57 reaches the lower end of

the chute 9, it will trip a tilting table 54, pivoted at 55, permitting contacts 58 and 59 to be closed by spring 52. This will complete a circuit from battery 61, through interrupter 62 winding of relay 63, and filament of lamp 64, causing the lamp to flash. Relay 63 energized closes its contact 69 and armature from ground at 70, through battery 67 and bell 60 to ground at 66 to furnish an audible signal to the attendant. This series of indicators operated by tilting table 54 serve to notify the attendant that a message has passed down the chute, and the annunciators 38 and 40 serve to indicate which particular lid (or lids) 10 has been opened. When the message is actually received at the basement office the attendant presses the button connected with the floor where the message was deposited to close a circuit through an indicating lamp 27 to notify the customer that the message has been received in the basement telegraph office.

Referring to Fig. 2, an incoming and outgoing pneumatic tube system 18 and 19 connects the basement office with a convenient branch telegraph or cable, central office 76. Tubes may be provided to several different offices if preferred dependent upon traffic conditions, that is whether the basement office has direct access to a cable office as distinguished from a land telegraph office. The received messages are passed over the operator's desk 74 having a telegraph line leading therefrom to a distant point not shown.

In Fig. 3 a circuit arrangement is shown by which lids 10 may be locked or unlocked by the attendant. Battery 45 is connected with the centre of a pole changing switch 44. A polar relay 25 is associated with each chute opening. The armature of this relay is adapted to rest in either of two positions depending on the direction of the current flowing through its coil 25 which is controlled by switch 44. The armature 24 is pivoted at 26 and carries an L shaped projection which in one position will engage a notched projection 77, attached to lid 10 and lock the lid down. When the current is reversed in the coil of the relay, the L shaped projection 24 will clear the notched projection 77 and the lid 10 of the box 11 may then be opened. Relay 25 is connected with the pole changing switch through conductors 43 and 46.

What is claimed is:

1. In a telegraph message collection system and in combination a subscriber's mailing receptacle, a forwarding office, a mailing chute connecting the mailing receptacle with the forwarding office for conducting and delivering messages deposited in the mailing receptacle to the forwarding office, a polarized relay associated with said mailing receptacle operable to lock the same against use, and

means at the forwarding station for operating said polarized relay.

2. In a mailing chute receptacle and in combination a door operable to permit access to the mailing chute, and means including a polarized relay operable to lock and unlock said door. 70

3. In a mailing chute receptacle and in combination a door operable to permit access to the mailing chute, a polarized relay controlling means for locking said door and remotely controlled circuit means for operating said relay. 75

4. In a telegraph message collection system, a chute for transmitting messages said chute having a plurality of subscribers' mailing receptacles and forwarding station to which said chute extends, signals at said forwarding station and said subscribers' stations for selectively signalling the deposit and receipt respectively of a message, a pneumatic tube system at said forwarding station for retransmitting the received message to a telegraph office, a polarized relay associated with each subscriber's receptacle operable to lock the same against use and means at said forwarding station for operating said relay. 80 85

In witness whereof, I hereunto subscribe my name this 27th day of September, 1929.
